HYDRAULIC LOOM CHECK

Roy O. Balogh, Cleveland, Ohio, assignor to The Weatherhead Company, Cleveland, Ohio, a corporation of Ohio

Application October 12, 1946, Serial No. 702,953

2 Claims. (Cl. 139—161)

1

This invention relates to a loom mechanism, more particularly to the provision of a novel hydraulic checking apparatus for the picker staff of the loom. This invention is a modification of the device described in my co-pending application, Serial No. 670,252, filed May 16, 1946, now Patent No. 2,483,517, issued October 4, 1949.

Modern practice in the weaving art tends towards a steady increase in loom operating speed. One of the problems encountered when attempting to increase the speed of the loom involves trouble with the operation of the shuttle and picker staff. It has been found that if the picker staff is not checked and brought smoothly to a stop at the end of its return stroke, without oscillation or rebound, that the shuttle is not always received in a predetermined position and erratic casting of the shuttle to the opposite side of the loom results. Early picker checks have included leather straps which have proven unsatisfactory particularly where the humidity of the atmosphere is subject to variation. Also, such straps are unsatisfactory in that they do not permit accurate adjustment and do not eliminate rebound. The prior art also discloses various pneumatic checks which have proven inferior in that the tendency of the compressed air to re-expand as the picker staff comes to rest results in serious rebound and poor operation.

I am aware that the broad concept of a hydraulic check for the picker staff is disclosed in the prior art but prior hydraulic devices are subject to numerous objections and have been found unsatisfactory for high-speed operation. Hydraulic checks of the prior art have not been connected to the picker staff but have been merely placed in its path like the old strap or pneumatic check, so that the staff strikes the check operating mechanism towards the end of the return cycle. This arrangement has proven undesirable in that the staff suddenly strikes the check arrangement while moving rapidly, resulting in rebound and erratic operation. This invention, like that described in my aforesaid application, has for an object the elimination of the undesirable characteristics of an abruptly engaged check mechanism by attaching the check mechanism to the picker staff at all times and so designing the check mechanism that it permits unchecked travel of the staff over certain portions of the stroke and provides a smooth checking operation for the end of the return stroke.

It is another object of this invention to provide a hydraulic means so that the staff is brought to a rest in an exceedingly smooth and positive

5 manner without any jarring or rebound. This is accomplished by providing a graduated or metered checking arrangement. Briefly, the principle of operation resides in the fact that at the beginning of the checking action where the velocity of the picker staff is high even though a relatively large amount of fluid is by-passed an effective checking action is produced. As the velocity of the staff is decreased, the fluid by-passing passage-way is correspondingly decreased which maintains an effective checking action. In this manner the checking action can be held substantially constant regardless of the picker staff velocity so that the picker staff is brought to a smooth stop without rebound.

10 It is customary in loom construction to move the picker staff on its power or shuttle casting stroke with positively acting mechanism and to return the picker staff to its retracted position with a spring or weight mechanism, there being lost motion in the casting mechanism so that final return may be effected by means of the spring or weight. In many looms the spring serves the 15 dual function of returning the staff and holding the lower end of the staff in position on a supporting plate. The spring arrangement just described will tend to bring the staff to its completely retracted position before the staff receives the shuttle. If a hydraulic dampening mechanism is present under these conditions this 20 means that the position of the staff in its return stroke when the shuttle strikes it depends upon the delicate construction of the damping orifices. The shuttle might strike the staff towards the 25 beginning of the damping stroke or, if the return spring is strong, the staff might be in a completely retracted position when the shuttle strikes it. This results in non-uniform casting of the shuttle or possible rebounding of the shuttle in 30 case the staff has come to rest when it receives the shuttle. It is an object of the present invention to insure that the shuttle cannot rebound by canceling the return spring pressure a short time 35 before the staff reaches its retracted position 40 whereby the inertia of the shuttle as it strikes the staff returns the staff to its retracted position. In my design I eliminate all chance of rebound of the shuttle by designing the check mechanism 45 so that the point of balance of a balance spring in the check mechanism and the return spring on the picker staff is somewhat near or at the point where the hydraulic checking action begins. In this manner the shuttle inertia moves the staff through the last part of its retract stroke against the uniform checking action of the checking de- 50

vice, and since my novel checking device is made adjustable, it is very simple to start the machine and adjust the mechanism for a given speed so that the shuttle and staff are brought to a smooth stop without rebound.

It is known in the art that check valves tend to wear and become troublesome after a period of operation. In a high-speed loom of the nature to which this check device relates, it is desirable to provide a check assembly which does not require a check valve. Accordingly, it is a further object of this invention to eliminate the check valve and still attain the objects referred to above.

Another object of this invention is to make the checking action readily adjustable while the device is in operation which I accomplish generally by providing for adjustment of a metering pin by remote control means.

A further object of the present invention lies in providing means whereby the final portion of the power stroke of the picker staff may be damped and in the provision of adjustable means to control the amount of damping action.

Another object of the present invention is to reduce the amount of machine work which must be done on the check body and to confine most of the machine work to the piston which design makes for economical manufacture.

These and other advantages of my invention will be apparent as the following description proceeds.

In the drawings:

Fig. 1 is a simplified view of the picker staff in the loom showing how my hydraulic check mechanism is connected thereto;

Fig. 2 is a longitudinal sectional view through my hydraulic check mechanism; and

Fig. 3 is a cross-sectional view taken at 3—3 of Fig. 2.

Referring to Fig. 1, a portion of the loom frame is indicated at L. The picker staff is shown at S and arm A operated by conventional loom mechanism moves the staff on a power stroke to cast the shuttle. The improved check mechanism is shown at C. In accordance with conventional practice a track 1 is provided for the shuttle 2 and a head 3 on the picker staff throws the shuttle across the loom when the staff is advanced on the power stroke. The picker staff itself is mounted in a shoe 4 which has a curved surface 5 for rolling on the supporting plate 6, the purpose of this arrangement being to approximate a straight line motion of the head 3. Plate 6 has an integral socket 6a for reception of the rock shaft 17 serving as a loom check supporting bar. One end of the assembly is supported by the loom frame as at 18. A flexible strap 7 is passed over an extension 8 of the picker staff and fastened at 9. A spring drum 10 is mounted as at 11 on the plate 6 and the drum is spring urged to move the picker staff in its retracted position as indicated by the arrow. This description of the picker staff mounting is merely given as a background for explaining the present invention, the details thereof are immaterial so far as the present invention is concerned. Any convenient fastening means 14 may be provided to link a rod 15 to a lever 16 in the hydraulic mechanism C. The spring 30 (Fig. 2) is the balancing spring previously referred to in the general description, one end thereof connects to a movable part of the check whereas the other end is supported by housing of the hydraulic mechanism as will hereinafter be more fully described. The retracting force of the spring in drum 10 is balanced at some posi-

tion before the picker staff reaches its fullest retract position by spring 30. For example, assume that the shuttle 2 is approaching the head 3. The picker staff has come to rest a certain distance before it engages the positive stop 19 so that the remainder of the staff travel absorbs shuttle inertia. The check C is mounted so that link 16 moves in the same plane as that of the picker staff.

The check C has a body or house portion indicated generally as at 20 which has a cylinder bore 21 formed at one end thereof, the bore being closed by a closure cap 22. A piston member P, which forms the movable part of the checking elements, has a cylindrical end portion 23 for engaging the walls of cylinder 21. The other end of the housing has a cylinder 25 in which fits piston portion 26. The cylinder 25 is closed by an apertured end cap 27 and suitable sealing members are provided in conjunction with both caps 22 and 27 to prevent escape of fluid under pressure. Thus, the piston is mounted for reciprocation within the housing 20 and supported at each end there being an intermediate chamber or reservoir 24 to receive a supply of fluid such as oil or any other suitable material. The balance spring 30 which overcomes the effect of the loom spring mounted in drum 10 referred to previously, may be mounted inside the cylinder, the fixed end being looped over a bar 31 which bar is urged against a shoulder 31a on the housing by the spring. The other end of the spring is mounted in the piston by means of a special member 32 which has portions removed to permit the loop of the spring to hook over a bar 32a on the washer. Washer 32 may be retained in the piston by snap ring 33 or any other convenient structure.

As will be described presently, as seen in Fig. 2 the right end of the piston acts to check the final portion of the power stroke whereas the left end of the piston acts to check a substantial portion of the return stroke. The left hand portion of the piston has an aperture 40 which communicates with metering aperture 41 which, in turn, communicates with an open end 42 of the piston. The passageways 40 and 41 provide for fluid communication during the final checking action. In order to permit an initial part of the return stroke to be unchecked, one or more passageways 43 may be drilled in the piston from the open end thereof which communicate with an annular reduced portion 44. With this arrangement there is free communication from the chamber 42 and the reservoir 24 when the piston is far enough to the right for annular chamber 44 to be opened to the reservoir. The metering pin has a tapered portion 47 which merges with a cylindrical portion 47a and I prefer that the diameter of the cylindrical portion 47a be slightly smaller than the metering aperture 41 in order to prevent a hydraulic block in case of maladjustment. The metering pin is threaded as at 48 to engage mating threads in the end cap 27 and may have an end member 49 which is turned by member 50 operated by a remotely controlled flexible shaft and handle arrangement indicated generally at H. The details of the flexible shaft form no part of this invention and I contemplate that any suitable means may be employed to rotate the metering pin. I may mount this flexible-shaft assembly by means of collar 51 attached to the cable guide and nut 52 threaded to the cap 27 on the check device.

The operating lever 16 may be pivoted as at 53 to a fixed part of the housing, the inner end

of the lever being pivotally connected to an operating block 61 by pivot means 62. A flexible cover 64 is provided. The operating block may fit in a guide recess or aperture 63 in the piston, the arrangement being such that rotation of lever 16 reciprocates the piston P within the cylinders. A by-pass passageway 35 connects the reservoir to the cylinder 21 and the flow through this passageway may be regulated by a metering screw 36 threadedly attached to the housing 20 in any convenient manner.

In describing the operation of the device, the relationship of parts shown in Fig. 2 is that which occurs when the picker staff is substantially at rest and ready for a power stroke as indicated in Fig. 1. As the arm A starts the staff on the power stroke the piston P is moved to the right and fluid in chamber 21, displaced by the portion 23 of the piston, can pass through apertures 34 in the piston and into the reservoir. This action continues until towards the end of the power stroke when apertures 34 are closed off by the wall 21 of the cylinder. Now, any additional fluid displaced to the reservoir must flow through the bleed passageway 35. Depending upon the adjustment of the metering pin 36, this provides a final checking or damping action to insure smooth operation during the end of the power stroke.

On the return stroke the piston is moved to the left whereupon fluid reverses its flow through the passageway 35 and passes from the reservoir into the chamber 21. This arrangement provides a certain amount of resistance to the initial portion of the return stroke but ample power is available in the loom mechanism to overcome this resistance. After a small portion of the return stroke has been completed apertures 34 again open to the reservoir and then begins an unchecked portion of the return stroke. However, the parts are arranged so that before the return stroke is completed tapered portion 47 in the metering pin begins to enter metering aperture 41. Likewise, the by-pass annulus 44 is being closed off by the edge 45 of the cylinder, and as the annulus 44 is closed off fluid is forced in the small space between the metering pin and its aperture. This begins the graduated or progressive checking action, and due to the taper of the metering pin the fluid restriction increases as the end of the return stroke is approached. When the tapered portion of the pin first enters the metering aperture the piston is traveling rapidly and the by-pass orifice is relatively large. Although a substantial amount of fluid can be displaced, since the piston is moving rapidly the fluid velocity and hence the checking action will be appreciable. As the return stroke continues, the effective by-pass aperture is steadily decreased but the piston velocity decreases with it, so that checking action may be maintained substantially constant. This action continues until the piston is brought to a smooth stop at the end of its return stroke. I have found that with the type of loom construction illustrated that no check valve is required for the initial part of the next power stroke. The operating member A is generally operated by means having sufficient power to rapidly initiate the next power stroke even though there will be a tendency for a vacuum to build up in chamber 42 requiring rapid reversed flow of fluid from the reservoir past the metering pin 41. However, with the balance spring construction illustrated, wherein the spring 30 balances the picker staff spring before the end of

its return stroke, the amount of hydraulic checking required to bring the parts to a smooth stop is not excessive and it is possible to provide a large enough orifice between the metering pin and the metering orifice to permit action to take place without the use of a check valve. The adjustable metering pin 37 can be set so that the final checking action of the cylinder absorbs the inertia of the rapidly moving shuttle as it strikes the picker staff, the yoke 13 of the driving arm A having enough clearance to permit the picker staff to come to rest before the completion of its return stroke. If balancing spring 30 is omitted, the device can be made operative by adjusting the metering pin to produce a slightly greater checking action in order to prevent the picker staff from bouncing against the stop portion 19 of the loom. This slightly greater checking action would be necessary if spring 30 were omitted because now the hydraulic units must check the spring 10 in the loom as well as the entire inertia of the picker staff. It is also understood that I can contour the tapered portion 47 of the metering pin to produce any desirable characteristics of ratio between picker staff velocity and checking action.

Although I have illustrated a preferred embodiment, it is understood that various modifications can be made therein without departing from the spirit of the invention, and I contemplate that the appended claims rather than the aforescribed embodiment be determinative of the scope of my invention.

Having thus described the present invention so that others skilled in the art may be able to understand and practice the same, I state that what I desire to secure by Letters Patent is defined in what is claimed.

What is claimed is:

1. A hydraulic check device for the picker staff of a loom comprising a fluid reservoir, a pair of cylinders each having one end closed and the other end opening to the reservoir, a piston in each cylinder, means to by-pass fluid from each cylinder to the reservoir, means to close off the associated by-pass means as a piston moves a substantial distance into a given cylinder, means for operatively connecting the pistons to the picker staff so that as one piston enters its cylinder the other is withdrawn from its cylinder, fluid metering means operative to check motion of said piston in one direction after the associated by-pass has closed, said fluid metering means comprising a fluid passageway leading from one cylinder to the reservoir formed in one of associated piston and cylinder means, and means carried by the other of said associated piston and cylinder means for progressively closing off said passageway in proportion to the position of the piston in the cylinder as the piston continues to enter the cylinder and spring means associated with said check device urging the piston in the other direction, past the midpoint of the stroke.
2. A hydraulic check device for the picker staff of a loom comprising a housing having formed therein a fluid reservoir and a pair of cylinders, each cylinder having one end closed and the other end opening to the reservoir, a piston having an element fitting in each cylinder, means to by-pass fluid from each cylinder to the reservoir, means to close off the associated by-pass means as a piston moves a substantial distance into a given cylinder and before the piston completes its stroke, means for operatively connecting the

pistons to a loom picker staff so that as one piston portion enters its cylinder the other is withdrawn from its cylinder, and fluid metering means for one cylinder and its associated piston element operative to check further entry of the piston element into said one cylinder after the by-pass associated with said one cylinder has closed, said fluid metering means comprising a fluid passageway formed in one of said associated piston and cylinder elements and leading from said one cylinder to the reservoir and means carried by the other of said associated piston and cylinder elements for progressively closing off said passageway as the piston element continues to enter said one cylinder after the by-pass means therefor has been closed, and spring means connected with said check device and arranged so as to urge said piston in a direction to withdraw said piston element from said one cylinder after said associated by-pass has been closed, said spring means continuing to urge said piston in the afore-

10 said direction after the piston has reached a mid-position wherein the by-pass means for both cylinders are equidistant from their associated closure means.

8 ROY O. BALOGH.
